UNITED STATES PATENT OFFICE.

EDWARD McCORMICK AND HENRY C. ROGGENKAMP, OF CHICAGO,
ILLINOIS.

ANGLE-COCK.

No. 841,806.

Specification of Letters Patent.

Patented Jan. 22, 1907.

Application filed August 6, 1906. Serial No. 329,376.

To all whom it may concern:

Be it known that we, EDWARD McCORMICK and HENRY C. ROGGENKAMP, citizens of the United States, residing at Chicago, in the county of Cook and State of Illinois, have invented certain new and useful Improvements in Angle-Cocks; and we do hereby declare the following to be a full, clear, and exact description of the invention, such as will enable others skilled in the art to which it appertains to make and use the same.

Our invention relates to the construction of angle-cocks, such as are applicable to the train brake-pipes of railway-cars equipped with automatic air-brakes, and has for its object the production of a simple and efficient angle-cock of such character that the closing thereof when the air-brakes are operatively connected to their source of pressure causes the engineer to be certainly and reliably informed of the condition of his braking control over the train.

As is well known, the closure of one of the angle-cocks of the type now commonly employed in air-brake systems deprives the engineer of the control of the brakes upon all those cars which are thus cut off from the main reservoir upon the locomotive and this without any warning that the brakes upon such cars are not available.

The invention, generally stated, may be said to consist in an angle-cock so constructed that through a system of ports in the valve and valve-bushing the closing thereof permits air from the train-pipe to pass into an exhaust chamber or reservoir, thus causing a moderate reduction of air-pressure in the train-pipe, with the consequent moderate or so-called "service" application of the brakes.

A further feature of the invention consists in the arrangement of ports by which the exhaust reservoir or chamber is opened to the atmosphere when the angle-cock is open.

There are other features of invention residing in particular combinations and elemental construction, all as will hereinafter more fully appear.

For the purpose of explaining this invention it is unnecessary to describe the manner in which the reduction of pressure in the train-pipe causes the operation of the piston in the brake-cylinder through the intermediary of the auxiliary reservoir and the triple valve, since the construction and functions

of these several parts of the air-brake system 55 are well known, and no modifications are necessary therein in order to apply the angle-cock of this invention.

In the drawings chosen for the purpose of illustrating our invention, the scope whereof 60 is pointed out in the claims, Figure 1 is a vertical longitudinal section of an angle-cock embodying our invention, the cock being shown in open position. Fig. 2 is a plan view of the angle-cock shown in Fig. 1. Fig. 3 is 65 an enlarged horizontal section of the conical plug or valve and its bushing, taken in the plane of the line 3 3, Fig. 6, the angle-cock being shown in open position. Fig. 4 is an enlarged horizontal section similar to Fig. 3, 70 but showing the relative positions of the valve and bushing ports when the cock is partially closed. Fig. 5 is a view similar to Figs. 3 and 4, but illustrating the position of the ports when the cock is fully closed. Fig. 75 6 is an enlarged vertical central section of the conical valve and bushing, taken in the plane of the line 6 6, Fig. 3, the cock being illustrated as fully open. Fig. 7 is a horizontal section of the valve and bushing, taken in the 80 plane of the line 7 7, Fig. 6.

Like symbols refer to like parts wherever they occur.

We will now proceed to describe our invention more fully, so that others skilled in the 85 art to which it appertains may make and use the same.

In the drawings, 1 is the angle-cock casing, which may be of a form such as now in common use—that is to say, a cast-iron casing 90 having a train-pipe conduit 2, provided at opposite ends with threaded portions 3 and 4, by which the train-pipe and air-brake hose, respectively, may be attached, and having also a conical opening or passage extending 95 transversely through the casing and intersecting the train-pipe conduit 2.

Within the transversely-extending conical passage of the casing 1 is a corresponding conical or tapered bushing 5, which is preferably of brass and which is provided with the usual train-pipe ports 6 and 7, opening into the conduit 2 of the casing. In addition to the usual train-pipe ports the bushing 5 is provided with one or more, but preferably 105 two, diametrically-disposed auxiliary ports 8, which open into an exhaust-chamber 16, and which extend upwardly in the interior con-

ical surface of said bushing a sufficient distance to afford free communication with the train-pipe ports of the valve 9 when the latter is in a proper position. These auxiliary ports 8 are of less length than the bushing and are formed in said bushing 5 at points sufficiently distant from the train-pipe ports 6 and 7 to prevent any leakage of air therethrough from the train-pipe when the angle-cock is either fully opened or fully closed. At least one of the auxiliary ports 8 extends upwardly a sufficient distance to be uncovered by an auxiliary port 12, which is formed in the conical valve 9 and which opens into the atmosphere, such upwardly-extending portion 8^a of the auxiliary port 8 being preferably somewhat constricted in order to eliminate any possibility of air escaping therethrough except when the angle-cock is entirely open.

Housed within the bushing 5 is the conical valve or tapered plug 9, which is commonly formed of brass and which is provided with the usual train-pipe ports 10 and 11, corresponding, respectively, to the similar ports 6 and 7 of the valve-bushing. Formed in the outer surface of the valve 9 is a small auxiliary groove or port 12, which opens out into the atmosphere and which leads downwardly a sufficient distance such that it overlaps and is in communication with the constricted portion 8^a of the auxiliary port 8 of the bushing when the said valve 9 is in a fully-opened position. By this means, as will hereinafter appear, the closed or substantially closed exhaust-chamber 16 is vented to the atmosphere whenever the angle-cock is entirely open.

The upper end of the valve 9 is provided with the usual squared lug or other suitable means for the attachment of an operating handle, such as 13, by a rivet or otherwise.

The conical valve may be maintained in proper relation with its bushing and wear of the parts be taken up in any suitable manner; but for this purpose it is preferred to tap the said valve centrally of its base and to thread thereinto a spring-pressed stem or pin 14, which bears upon the upper end of a spring 15, seated upon the bottom of the exhaust-chamber 16, as shown.

Attached to the angle-cock casing 1, either by being threaded thereon or in any manner suitable to form an air-tight or substantially air-tight joint, is the exhaust-chamber 16. This exhaust-chamber, the volume of which is sufficient to cause the desired reduction (say from five to eight pounds) in the train-pipe pressure whenever the air in the train-pipes is permitted to flow into it, may be entirely closed, if desired; but in order to permit the escape of any water of condensation it is preferred to thread into the bottom thereof a plug 17, in which a very small hole is drilled. By this means the exhaust-chamber operates substantially as a closed reser-

voir during the period the air from the train-pipe is being exhausted into said chamber. In lieu of the drilled plug 17 any drain-cock of well-known construction may be employed to relieve the chamber of water of condensation.

In order to facilitate the application and removal of the exhaust-chamber 16, a hexagonal wrench-seat, such as 18, may be provided.

The construction of the angle-cock being substantially such as hereinbefore pointed out, its operation will be as follows: When the cock is fully open, as shown in Figs. 1, 2, 3, 6, and 7, it will be observed that the exhaust-chamber 16 is in communication with the atmosphere through that auxiliary port 8 of the bushing which has the constricted extension 8^a and thence through the auxiliary port 12 of the valve 9. In this position of the valve the train-pipe conduit 2 is cut off from the exhaust-chamber 16, and consequently from the atmosphere, by reason of the fact that the solid walls of the conical valve 9 close the auxiliary ports 8 of the bushing 5. As the conical valve 9 is turned from an open to a closed position it will be seen that through the train-pipe ports of the valve and bushing and through the auxiliary ports 8 of the latter the train-pipe conduit 2 and attached train-pipe and air-brake hose are placed in communication with the exhaust-chamber 16. At this time the auxiliary port 12 of the valve 9 does not overlap the constricted portion 8^a of the port 8 in the bushing, so that the air from the train-pipe exhausts into a closed or substantially closed chamber. By this means a limited and moderate reduction of pressure in the train-pipe is accomplished and the exhaust is retarded in character, so that a sudden or emergency application of the brakes does not occur.

While a single auxiliary port 8 may be employed to accomplish the same purposes as a plurality of ports, yet it is preferred to use two ports, such as 8, as by this means the ports may be made of such dimensions and so located that there is no possibility of leakage, while at the same time the combined area of said ports is sufficient to insure the proper operation of the device when the valve 9 is closed very quickly.

When the valve 9 is turned to a fully closed position, as shown in Fig. 5, the train-pipe conduit 2 is entirely cut off from the exhaust-chamber 16, since the solid walls of the conical valve 9 close the train-pipe ports 6 and 7 of the bushing. The air withdrawn from the train-pipe is thus trapped in the exhaust-chamber 16 and in the hollow interior of the valve 9.

When the angle-cock is next fully opened, the auxiliary port 12 of the valve 9 comes into alignment with the portion 8^a of the

auxiliary port 8 of the bushing, and the air within the chamber 16 is exhausted to the atmosphere.

It will be noted that by the use of this angle-cock the brakes throughout the train are set whenever such angle-cock is closed, but that the engineer may regain control of the brakes upon all those cars between the engine and the angle-cock so closed by simply increasing the pressure in the train-pipes of the forward cars in the usual manner.

It will also be noted that augmented and nearly instantaneous or so-called "emergency" applications of the brakes do not occur when the angle-cock of this invention is closed, since, as is well known, a sudden or great diminution of the train-pipe pressure is necessary to cause the triple valve to permit such emergency application of the brakes.

When an angle-cock embodying this invention is closed, in addition to causing the setting of the brakes, as heretofore described, the air passing through the ports of the angle-cock causes a plainly-audible sound in the engineer's brake-valve similar to that heard when the train-line is recharged.

Having thus described our invention, what we claim, and desire to secure by Letters Patent, is—

30 1. An angle-cock having a casing provided with a conduit, a valve adapted to close the conduit in said casing, and an exhaust-chamber which is placed in communication with the casing-conduit by an operative movement of said valve.

2. An angle-cock having a casing provided with a conduit, a valve adapted to close the conduit in said casing, and an exhaust-chamber which communicates with the casing-conduit when the valve is in an intermediate position but not when the said valve is either fully opened or fully closed.

3. An angle-cock having a casing provided with a conduit, a valve adapted to close the conduit in said casing, means whereby a reduction of fluid-pressure in the casing-conduit is permitted during a closing movement of said valve and a reduction of pressure is prevented after the valve is closed, and means for limiting the reduction of pressure in said conduit.

4. An angle-cock having a casing provided with a conduit, a valve adapted to close the conduit in said casing, and an exhaust-chamber which is placed in communication with the casing-conduit during a closing movement of the valve and which is placed in communication with the atmosphere when the valve is opened.

5. An angle-cock having a casing provided with a conduit, an exhaust-chamber adapted to be dissimultaneously placed in communication with the casing-conduit and with the atmosphere, and means for dissimultaneously placing the exhaust-chamber in com-

munication with the casing-conduit and with the atmosphere.

6. An angle-cock having a casing provided with a conduit, a valve adapted to close the conduit in said casing, means whereby a reduction of fluid-pressure in the casing-conduit is permitted during a closing movement of said valve and a reduction of pressure is prevented after the valve is closed, and means for causing a retarded reduction of pressure during the closure of said valve.

7. An angle-cock having a casing, a valve, a valve-bushing, and an exhaust-chamber, said valve and said valve-bushing having train-pipe ports, and said bushing having an auxiliary port which opens into the exhaust-chamber and which is adapted to communicate with a train-pipe port of the valve when the latter is in an intermediate position but not when said valve is either fully opened or fully closed.

8. An angle-cock having a casing provided with a conduit, a valve, and a valve-bushing, said valve and valve-bushing each having train-pipe ports, and said bushing having an auxiliary port which communicates with the casing-conduit through a train-pipe port of the valve when the latter is in an intermediate position but not when said valve is either fully opened or fully closed.

9. An angle-cock having a casing provided with a conduit, a valve, a valve-bushing, and an exhaust-chamber, said valve having train-pipe ports and an auxiliary port which communicates with the atmosphere, and said bushing having train-pipe ports and an auxiliary port which opens into the exhaust-chamber and which is adapted to dissimultaneously communicate with a train-pipe port of the valve and with the auxiliary port thereof.

10. An angle-cock having a casing provided with a conduit, a valve, and a valve-bushing, said valve and bushing each having train-pipe ports, and said bushing having a plurality of auxiliary ports which communicate with the casing-conduit through the train-pipe ports of the valve when the latter is in an intermediate position but not when said valve is either fully opened or fully closed.

11. An angle-cock having a casing provided with a conduit, a valve, a valve-bushing, and an exhaust-chamber, said valve having train-pipe ports and an auxiliary port, and said bushing having train-pipe ports and a plurality of auxiliary ports which open into the exhaust-chamber, one of said auxiliary ports of the bushing being adapted to dissimultaneously communicate with a train-pipe port of the valve and with the auxiliary port thereof.

12. An angle-cock having a casing provided with a conduit, a valve, a valve-bushing, and an exhaust-chamber, said valve and

- said bushing each having train-pipe ports, and said bushing having a plurality of auxiliary ports which open into the exhaust-chamber and which are adapted to communicate with the casing-conduit through the train-pipe ports of the valve when the latter is in an intermediate position but not when said valve is either fully opened or fully closed.
- 10 13. An angle-cock having a casing provided with a conduit, a valve provided with train-pipe ports and an auxiliary port, a valve-bushing provided with train-pipe ports and an auxiliary port which opens into the exhaust-chamber and has a constricted portion, and an exhaust-chamber, said auxiliary port of the bushing being adapted to communicate with the casing-conduit through a train-pipe port of the valve when the latter is in an intermediate position but not when said valve is either fully opened or fully closed, and being adapted through its constricted portion to communicate with the auxiliary port of the valve when the latter is fully opened.
- 15 14. An angle-cock having a casing provided with a conduit, a conical valve adapted to close said conduit, a conical valve-bushing, an exhaust-chamber, and a spring housed within the exhaust-chamber and forming a support for the said valve, said conical valve having train-pipe ports and an auxiliary port which communicates with the atmosphere, said bushing having train-pipe ports and a plurality of auxiliary ports which open into the exhaust-chamber, the said auxiliary ports of the bushing being adapted to communicate with the casing-conduit through the train-pipe ports of the valve when the latter is in an intermediate position but not when said valve is either fully opened or fully closed, and the auxiliary port of said valve being adapted to communicate with one of the auxiliary ports of the bushing when the valve is fully opened.
- 20 15. An angle-cock having a casing provided with a train-pipe conduit, a valve adapted to close said train-pipe conduit of the casing, said valve having train-pipe ports therein, means whereby air is permitted to escape from the said conduit through the train-pipe ports of said valve during the movement of said valve from open to closed position but no air is permitted to escape after said valve is closed, and means for retarding the escape of the air.
